SPINNING CENTRIFUGES FOR
ARTIFICIAL SILK

Walter Zinselmeyer, Remscheid-Lenne, Germany, assignor to American Bemberg Corporation, New York, N. Y., a corporation of Delaware

Application May 4, 1932, Serial No. 609,302
In Germany May 4, 1931

11 Claims. (Cl. 117—27.6)

This invention relates to an improvement in spinning centrifuges for use in the manufacture of yarn of artificial origin.

The spinning centrifuge which forms the subject matter of this application is intended for use in the spinning of artificial silk and is such that the thread guide funnel is driven directly from the motor which operates the spinning pot.

In order to produce satisfactorily spun cakes it is necessary accurately to adjust the stroke of the thread guide funnel both as regards position and length to the height of the spinning pot, since the smallest deviations, owing to the summation of the errors at each winding, cause considerable displacement of the filament layers, the spun cakes being flattened at the ends when the stroke is too small or being compressed when the stroke is too large.

This disadvantage is avoided by the invention by making the stroke of the thread guide funnel adjustable during the operation. For this purpose the curve drum used for controlling the motion of the thread guide funnel is mounted so as to be axially displaceable and it is given an additional up and down motion, the stroke of which can be adjusted while the apparatus is working. For this purpose the curve drum 61 at its lower end is provided with an internal flange 62. The lower surface 75 of this flange 62 is intended as a trackway for passing over the roller 73.

Preferably, however, several curves are not distributed over the drum but a single guide curve is employed which is compounded from the several guide curves. Curves of varying diameter are advantageously placed coaxially one within the other so that they form a curved guide which is indicated by the lower surface 75 of the flange 62 and which possesses varying inclinations in a radial direction over the circumference as well as having a circumferentially undulating contour.

The engagement with the various curves, now lying in one surface, is attained by axial displacement of the guide element or pin.

The invention has the advantage that the requisite stroke of the thread guide funnel can be adjusted even while the apparatus is working in the simplest possible manner. This is important since the stroke cannot be determined from the outset according to the height to which the spun cake is to be wound but this stroke has to be adjusted according to the varying conditions, more particularly the various thread titres. Furthermore, the device provided by this invention enables different spinning pots to be employed without any bother for making spun cakes of

varying heights, since the stroke can be readily adjusted each time.

The accompanying drawing shows by way of example one constructional form of the apparatus provided by this invention. 5

In the drawing, the spinning pot is indicated by the reference numeral 1, and is rotated by a motor 2. A thread guide funnel 3 extends within the center of the pot 1 for the usual purpose of guiding the filaments. The thread 10 guide 3 is secured to a thread guide rod 4 which is reciprocated through the medium of a pin 5 at its lower end and a rotating drum 61 with a cam way 6 through which the pin 5 extends. The motor 2 has a shaft extension 7 which rotates in a stationary bearing sleeve 59. A pinion 8 is fixed on the shaft 7 and meshes with another pinion 9 on a short shaft 10 having a pinion 11 at its upper end which meshes with a gear 12 on another short shaft 13 having a pinion 14 meshing with an internal ring gear 17 toothed at 67. The ring gear 17 rotates around the bearing sleeve 59.

The drum cam 61 rotates with the gear 16 but is axially slidable with relation to it by reason 25 of a key and slot arrangement. The key 17 is secured in the sleeve 76 of the gear 17 and is slidable in the groove 16 which is cut in the bearing of the drum 61. The drum 61 is spring 30 pressed downwardly at 15 against a roller 73 for a reason later described.

It will be seen by reference to the drawing that the curve drum 61 is provided at its lower end with an internal flange 62. The lower surface 75 of the flange 62 is intended as a trackway 35 for passing over the roller 73. This trackway is circumferentially undulating and at the same time varyingly inclined to the horizontal radial axis of the cam drum 61.

The roller 73 which contacts with the trackway 75 is adjustably secured in the lower part 40 of the housing 68 and is radially adjustable with respect to trackway 75 by reason of the threaded shank 78. A lock nut 74 holds the shank 78 from displacement after an adjustment has been made. 45

By reason of the varying horizontal radial inclination of the trackway 75, it can be readily seen how an infinite number of curve variations 50 can be obtained by positioning the roller 73 toward the inner portion of the trackway 75 or by withdrawing it toward the outer rim of said trackway 75.

Having now particularly described and ascertained the nature of my said invention and in 55

what manner the same is to be performed, I declare that what I claim is:

1. In a spinning mechanism, a spinning pot, a motor for rotating said pot, a thread guide, means to reciprocate said thread guide, and means for varying the reciprocation of said thread guide, said means comprising a drum cam rotated by said motor, but axially movable with relation thereto, and means for axially displacing said drum cam, said means comprising a cam surface at the lower end of said drum cam, said cam surface varyingly inclined to the axis of said drum cam, and means for supporting the rotative passage of said drum cam, said last mentioned means being adjustably positioned with relation thereto.
2. In a spinning mechanism, a spinning pot, a motor for rotating said pot, a thread guide, means to reciprocate said thread guide, and means for varying the reciprocation of said thread guide, said means comprising a drum cam rotated by said motor, but axially movable with relation thereto, and means for axially displacing said drum cam, said means comprising a cam surface at the lower end of said drum cam, said cam surface varyingly inclined to the axis of said drum cam, at the same time circumferentially undulating, and means for supporting the rotative passage of said drum cam, said last mentioned means being adjustably positioned with relation thereto.
3. In a spinning mechanism, a spinning pot, a motor for rotating said pot, a thread guide, means for reciprocating said thread guide, and means for varying the reciprocation of said thread guide, said means comprising a drum cam rotated by said motor, but axially movable with relation thereto, and means for axially displacing said drum cam, said means comprising a cam surface comprising a flange at the lower end of said drum cam, said cam surface varyingly inclined to the axis of said drum cam and means for supporting the rotative passage of said drum cam, said last mentioned means comprising a roller radially adjustable across said lower surface of said flange.
4. In a spinning mechanism, a spinning pot, a motor for rotating said pot, a thread guide, means to reciprocate said thread guide, a means for varying the reciprocation of said thread guide, said last mentioned means comprising a drum cam rotated by said motor, but axially movable with relation thereto, and means supporting the rotative passage of said cam, said last mentioned means being adjustably positioned with relation thereto.

5. In a machine for manufacturing thread, a revolvable bucket, and an annular undulating means angularly arranged with respect to the bucket axis for directing thread undulatingly against the wall of the bucket.

6. In a machine for manufacturing thread, a revolvable bucket, and an annular concentric undulating surface angularly arranged with respect to the bucket axis for directing thread undulatingly against the wall of the bucket.

7. In a device for collecting thread, a revolvable bucket and means for delivering thread to the bucket, said means including a thread guide for directing the thread into the bucket, and annular means diagonally arranged about the bucket axis for imparting a traverse movement to the thread and to vary the position of said traverse movement.

8. In a device for collecting thread, a revolvable bucket and means for delivering thread to the bucket, said means including a thread guide for directing the thread into the bucket, and rotatable annular means diagonally arranged about the bucket axis for imparting a traverse movement to the thread and to vary the position of said traverse movement.

9. In a device for collecting thread, a revolvable bucket and means for delivering thread to the bucket, said means including a thread guide for directing the thread into the bucket, and annular means diagonally arranged about the bucket axis and rotatable in accordance with the rotations of said bucket for imparting a traverse movement to the thread and to vary the position of said traverse movement.

10. In a device for collecting thread, a revolvable bucket and means for delivering thread to the bucket, said means including a thread guide for directing the thread into the bucket, and an undulating annular surface about the bucket axis, which surface is angularly disposed to the bucket axis for imparting a traverse movement to the thread and to vary the position of said traverse movement.

11. In a device for collecting thread, a revolvable bucket and means for delivering thread to the bucket, said means including a thread guide for directing the thread into the bucket, and an undulating annular surface about the bucket axis, which surface is angularly disposed with respect to the bucket axis and rotatable in accordance with the rotations of said bucket for imparting a traverse movement to the thread and to vary the position of said traverse movement.

WALTER ZINSELMAYER.
